UNITED STATES PATENT OFFICE.

BERT A. ADAMS, OF POMONA, KANSAS.

HARNESS ATTACHMENT.

No. 857,916.

Specification of Letters Patent.

Patented June 25, 1907.

Application filed May 3, 1906. Serial No. 315,017.

To all whom it may concern:

Be it known that I, BERT A. ADAMS, a citizen of the United States, residing at Pomona, in the county of Franklin and State of Kansas, have invented a new and useful Harness Attachment, of which the following is a specification.

This invention relates to harness and its object is to provide an attachment for connecting a crupper strap to hip breeching so that the two straps will be held fixedly in proper relation to each other and the breeching will be prevented from moving upon the crupper but can at the same time be readily disconnected therefrom.

The invention consists of a plate adapted to be secured to the hip breeching and having grooves extending transversely therein to receive the crupper straps, said grooves being provided with strap engaging devices. A retaining spring or keeper extends over the grooves and serves to hold the straps in proper relation.

The invention also consists of certain other novel features of construction and combinations of parts which will be hereinafter more fully described and pointed out in the claims.

In the accompanying drawings is shown the preferred form of the invention.

In said drawings: Figure 1 is a plan view showing the device and straps assembled; and Fig. 2 is a longitudinal section.

Referring to the figures by numerals of reference, 1 is an arched plate adapted to be secured by means of rivets 2 or in any other suitable manner to a hip breeching and this plate is provided adjacent its center with grooves 3 which extend transversely of the plate and diverge rearwardly, each groove having an upstanding lug 4 upon the bottom thereof at the center. A retaining spring or keeper 5 is secured at its center upon the plate 1 and between the grooves and this spring rests close to the lug 4 and has its ends normally seated in recesses 6 formed in the plate 1 between its ends and the grooves 3. The central portion of the spring 5 is preferably enlarged as at 7 so that it will not be weakened by the insertion of securing screws 8:

The device herein described is adapted to

be secured upon the breeching 9 by means of rivets 2 and the crupper straps 10 are disposed within the grooves 3 with the lugs 4 projecting into openings therein. Spring 5 bears upon the straps and holds them within the grooves and in engagement with the lugs and therefore said straps and the breeching are held in fixed relation to each other. By raising the ends of the spring the crupper straps can be disconnected from the plate.

The device is very simple and very inexpensive in construction and can be readily connected to a harness, and will be found particularly serviceable in that it prevents the breeching from sliding backward upon the crupper.

What is claimed is:

1. An attachment for harness comprising a plate having a strap receiving groove extending transversely therein, a strap engaging lug within the groove, and a resilient keeper secured upon the plate and extending over the lug and groove.

2. An attachment for harness comprising a plate having diverging strap receiving grooves therein, strap engaging lugs within the grooves, and a resilient keeper secured upon the plate between the grooves and extending over said grooves and lugs.

3. An attachment for harness comprising a plate having diverging grooves extending transversely therein, strap engaging lugs within the grooves, a resilient keeper secured at its center upon the plate between the grooves, said keeper extending across the grooves and over the lugs, said plate having recesses constituting seats for the ends of the keeper.

4. In a harness the combination with a hip breeching; of a plate secured thereon and having a groove extending transversely therein, a lug within the groove, a resilient keeper secured upon the plate and extending across the groove and over the lug, and a crupper strap within the groove and engaged by the lug, said strap being retained by the keeper.

5. In a harness the combination with a hip breeching; of a plate secured thereon and having diverging transversely extending grooves in one face, lugs within the grooves,

crupper straps within the grooves and engaged by the lugs, and a resilient keeper secured upon the plate and bearing on the straps above the lugs, said plate having recesses constituting seats for the ends of the keeper.

In testimony that I claim the foregoing as

my own, I have hereto affixed my signature in the presence of two witnesses.

BERT A. ADAMS.
